[57] **CLAIM**

The ornamental design for an aspirating plunger for power injector cartridges, as shown and described.

DESCRIPTION

FIG. 1 is a perspective view of a aspirating plunger for power injector cartridges incorporating the design;
FIG. 2 is a side elevational view of the design of FIG. 1, the left side and the right side elevation having the same appearance;
FIG. 3 is a top plan view of the design of FIG. 1; and,
FIG. 4 is a bottom plan view of the design of FIG. 1.
